United States Patent Office

Des. 182,562
Patented Apr. 22, 1958

182,562

FOOD TRAY

Ray Bang, Brainerd, Minn.

Application July 3, 1957, Serial No. 46,829

Term of patent 14 years

(Cl. D58—26)

Fig. 1

Fig. 2

Figure 1 is a perspective view of a food tray showing my new design;

Figure 2 is an end elevational view thereof; and

Figure 3 is a developed plan view of the same.

The side and end not shown are the same as the side and end shown.

The characteristic features of the design are shown in full lines.

I claim:

The ornamental design for a food tray, as shown and described.
